UNITED STATES PATENT OFFICE.

MAX MITTENDORFF, OF WYOMISSING, PENNSYLVANIA, ASSIGNOR TO THE NARROW FABRIC CO., OF WEST READING, PENNSYLVANIA, A CORPORATION OF PENNSYLVANIA.

DESIGN FOR A TRIMMING BRAID FOR GARMENTS AND SIMILAR ARTICLES.

Application filed March 10, 1922. Serial No. 1,110. Term of patent 14 years.

To all whom it may concern:

Be it known that I, MAX MITTENDORFF, a citizen of the United States, residing at Wyomissing, in the county of Berks and State of Pennsylvania, have invented a new, original, and ornamental Design for Trimming Braid for Garments and Similar Articles, of which the following is a specification, reference being had to the accompanying drawing, forming part thereof.

The figure is a plan view of a trimming braid for garments and similar articles showing my new design.

I claim:

The ornamental design for a trimming braid for garments and similar articles, as shown.

In testimony whereof I affix my signature.

MAX MITTENDORFF.
